US00D572454S

(12) United States Design Patent
Dirsa

(10) Patent No.: US D572,454 S
(45) Date of Patent: * Jul. 8, 2008

(54) SHOE UPPER

(75) Inventor: David Joseph Dirsa, Beaverton, OR (US)

(73) Assignee: NIKE, Inc., Beaverton, OR (US)

() Term: 14 Years

(21) Appl. No.: 29/284,602

(22) Filed: Sep. 12, 2007

(51) LOC (8) Cl. 02-99

(52) U.S. Cl. D2/969

(58) Field of Classification Search D2/902, D2/906–908, 943, 944, 969, 972–974, 945; 36/45, 77 M, 77 R, 83, 113, 114, 126–131

(57) CLAIM

The ornamental design for a shoe upper, as shown and described.

DESCRIPTION

FIG. 1 is a front perspective view of a shoe upper showing my new design;

FIG. 2 is a lateral side view thereof;

FIG. 3 is a medial side view thereof;

FIG. 4 is a front view thereof;

FIG. 5 is a rear view thereof; and,

FIG. 6 is a top view thereof.

The broken line showing of the bottom edge of the shoe upper is for illustrative purposes only and form no part of the claimed design.

1 Claim, 5 Drawing Sheets
